WINDING APPARATUS

Emil Sirp, Downers Grove, Ill., assignor to Western Electric Company, Incorporated, New York, N. Y., a corporation of New York

Application May 15, 1943, Serial No. 487,082

7 Claims. (Cl. 153—87)

This invention relates to winding apparatus and more particularly to an apparatus for winding vacuum tube filament coils.

It is an object of the present invention to provide an apparatus for rapidly winding a coil with a high degree of accuracy.

In accordance with one embodiment of the invention, a manually rotatable shaft having a lead screw thereon is interconnected with a mandrel driving mechanism whereby the mandrel is rotated a plurality of times for each rotation of the lead screw and a guiding means driven by the lead screw is shifted axially of the mandrel to distribute wire on the mandrel in a highly accurate manner. The interconnection between the mandrel and the lead screw, after effecting the distribution of the wire axially of the mandrel, may be manually disconnected to facilitate insertion of a new mandrel in its driving means and permit the resetting of the guiding means. The mechanism is also provided with a stop actuated by the guiding means to stop the operation of the shaft and mandrel after a predetermined number of turns have been wound on the mandrel.

A better understanding of the invention may be had by reference to the following detailed description of one embodiment thereof when considered in conjunction with the accompanying drawings, wherein

Fig. 1 is a front elevational view of apparatus embodying the invention, parts being broken away to more clearly show some details of the feed screw and guiding mechanism;

Fig. 2 is a side elevational view of the apparatus shown in Fig. 1;

Fig. 3 is a fragmentary sectional view taken substantially along the line 3—3 of Fig. 2 in the direction of the arrows;

Fig. 4 is a fragmentary sectional view taken along the line 4—4 of Fig. 2 in the direction of the arrows;

Figs. 5 and 6 are plan and side elevational views of the mandrel on an enlarged scale and showing the servings of wire on the mandrel;

Fig. 7 is an end elevational view of the mandrel shown in Figs. 5 and 6.

In the drawings, wherein like reference characters designate the same parts throughout the several views, the apparatus is shown mounted upon a base 10, which may be mounted upon any suitable bench or table (not shown). The base 10 comprises an inverted T-shaped bracket having an upright portion 33 which has apertures 11 and

12 extending through it for receiving a main drive shaft 13 and a mandrel driving shaft 14, respectively. The main drive shaft 13 has a relatively large gear 15 keyed to it by means of a key 16. The key 16 also serves to lock a collar 17 to the shaft 13, a machine screw 18 and washer 19 being positioned to hold the collar 17 on the end of the shaft 13. Formed integrally with the collar 17 is a crank arm 20, on which there is mounted a handle 21, whereby rotation may be imparted manually to the shaft 13. A stud shaft 22 is set into the base member 10 and has freely rotatable thereon an idler 23 in mesh with the gear 15 and a gear 24, which is, in turn, keyed to the shaft 14.

Suitably formed on or attached to the shaft 13 is a distributor lead screw 30 and the shaft 13 is also provided with a retainer collar 31 and a reduced shank portion 32. The collar 31 cooperates with the collar 17 on the handle 20 to retain the shaft 13 on the upright portion 33 of the base member 10 and the shank portion 32 of the shaft 13 serves as a bearing on which a cylindrical portion 34 of a distributor block 35 is slidable and oscillatable. The distributor block 35 supports a shouldered rod 36, which is slidable in a shouldered aperture 37 formed in the block. Mounted on the upper end of the rod 36 is a pin supporting plate 38, which is fixed between a shoulder 39 on the rod 36 and a retainer nut 40, threaded on the upper end of the rod. At its right end (Fig. 2), the plate 38 carries a tapered pin 41, which, as shown most clearly in Fig. 1, is provided with a tapered or knife-edged point 42 adapted to engage the threads of the lead screw 30 when the rod 36 is in the position shown in the various views. The rod 36 is urged to the position shown in Figs. 1 and 2 by a compression spring 43 seated between a shoulder 44 of the aperture 37 and a shoulder 45 formed on the rod 36. The lower end of the rod 36 extends into a downwardly extending portion 46 of the block 35 and into engagement with a flat surface of a cam 47. The cam 47 is set into a slot 48 formed in the portion 46 of the block 35 and is attached to a reduced portion 49 of a manually operable cam shaft 50. The cam shaft 50 is rotatable in aligned apertures 51 and 52 formed in the portion 46 of the block 35 and is provided at its left end (Fig. 2) with a handle 53.

The right side of the block 35 has a pin 55 mounted in it to which is attached one end of a contractile spring 56, the lower end of which is attached to a pin 52, in turn mounted on a horizontally disposed member 53 attached to the up-

right portion 33 of the base 10. The horizontally disposed member 63 has a slot 64 formed in its upper surface, which is adapted to receive the extending rounded portion of the cam 47 when the cam 47 is in the position shown in Figs. 1 and 2 to lock the block 35 in the position shown in solid lines in Fig. 2, where the flat portions of the cam 47 will permit the spring 47 to move the rod 36 and tapered pin 41 downwardly to a position where the point 42 of the pin is in engagement with the lead screw 30.

At its upper right hand corner (Fig. 2), the block 35 carries a post 65, on which there is mounted a guide member 66. The guide member 66 has a central aperture 67, through which a filament wire 68 may be directed to guide the filament to a mandrel, designated generally by the numeral 69. The guide member 66 is milled away, as shown at 70 (Fig. 2), through half its diameter and a bent spring 71, attached to the post 65 by means of a screw 72, is bent down to bear on the wire 68 travelling in the milled out portion, as shown at 70 of the guide member 66.

In addition to supporting the guide member 66, the post 65 carries an adjustable abutment screw or member 73, which is threaded into the post 65 and locked in position by means of a lock nut 74. This abutment screw will, of course, travel with the post 65 and after the post 65 has travelled a predetermined distance to the right (Fig. 1), the abutment screw 73 will engage a pin 75 mounted upon a slide rod 76. The slide rod 78 is freely slideable in an aperture 77 formed in the upright portion 33 of the base member 10 and has a pin 78 mounted in it which extends through a slot 79 in the upright portion 33 to, in turn, engage in a slot 80 formed in the upright end of a lever 81. The lever 81 is pivoted on a pivot pin 82, threaded into the rear surface of the upright portion 33 of the base member 10 and has a slot 83 (Fig. 1) formed in its lower end. The slot 83 (Figs. 1 and 4) is adapted to receive a pin 84 fixed in a spring cylinder 85, which is, in turn, slideable in a recess 86 in the base member 10. The spring cylinder 85 has a knurled cap screw 87 threaded into its right end (Fig. 4) to compress a spring 88 against a head 89 of a locking plunger 90. When the lever 81 is rocked clockwise by a slide rod 76, the spring cylinder 85 will be moved to the left (Figs. 1 and 4) and will tend to move the locking plunger 90 to the left with it. The lefthand end (Fig. 4) of the locking plunger 90 abuts the right surface of the gear 15 (Figs. 1 and 4) and when the gear 15 reaches a predetermined point in its rotation, a recess 92 in the gear will be brought into alignment with the plunger 90 and if the plunger 90 is at that time being urged to the left by the spring 88, the plunger will move into the recess and effectively prevent further rotation of the gear 15. From the foregoing, it will be apparent that the distributor block 35 and some of the parts carried by it comprises a distributor assembly driven by the distributor lead screw 30 and that the mandrel 69 will be stopped in its rotation after the distributor assembly has moved far enough for the abutment screw 73 to engage pin 75 and through it actuate slide rod 76.

The mandrel 69, as shown in detail in Figs. 5 and 6, comprises a cylindrical body portion 100, which terminates in two semi-cylindrical portions 101 and 102. The body portion 100 of the mandrel 69 has a slot 103 formed throughout its length. The left end of the mandrel (Fig. 5), that is, the end of the mandrel which is to be

inserted in a mandrel head 104 of the shaft 14, is, as pointed out, semi-cylindrical to fit a matching socket 105 in the mandrel head 104. Adjacent the left end of the slot 103 (Figs. 5 and 6) 5 a pin 106 is set into the slot and when the mandrel is to have the wire 68 attached to it, the wire is pushed into abutting relation with the pin 106 after being inserted between the base of the slot 103 and a pin 107, which extends across the mandrel and serves to snub the wire 68 in the slot. The right end (Figs. 5 and 6) 10 of the mandrel 69 is slotted, as shown at 108, and a pin 109 mounted in the semi-cylindrical portion 102 of the mandrel extends a short distance above the flat surface thereof. After a coil 110 of filament wire has been wound on the mandrel and the winding mechanism stops, as 15 will be pointed out in connection with the description of the operation of the apparatus, the wire 68 may be bent around the pin 109 and around the semi-cylindrical portion 102 after passing it through the slot 108, thereby to attach the wire to the mandrel.

A more complete understanding of the operation of the apparatus may be had from the following brief description of the mode of operation thereof. An operator desiring to wind the filament coil on the mandrel 69 may first release the block 35 and rock it to its position shown in dot and dash lines in Fig. 2 and may then manually draw a short length of wire 68 from a supply (not shown) through the guide member 66 and may then insert the end of the wire in the slot 103 and under the pin 107, forcing the wire into abutting engagement with the pin 106. The length of wire between pins 106 and 107 20 will serve to provide a terminal for the wound filament and the wire, in being bent around the pin 107 and over the edge of the slot 103, will be locked to the mandrel tight enough so that the winding may be effected. After the wire has been inserted in the slot 103 just described, the mandrel may be placed in the mandrel head 104 and the block 35 rocked to its full line position, as shown in Fig. 2, it being understood that the length of wire between the guide member 66 and the mandrel should be maintained as short as 25 possible during this part of the loading operation. After the mandrel has been inserted in the mandrel head 104 and the block 35 has been locked in its full line position, as shown in Fig. 2, by manipulation of the handle 53, the cam 47 will lock the block 35 in position and will permit the spring 43 to move the tapered pin 41 into engagement with the threads of the lead screw 30, it being understood that the block 35 should be pushed into engagement with the upright portion 33 of the base 10 before the tapered pin 41 is engaged with the lead screw 30. After 30 the pin 41 has been engaged with the lead screw 30, the handle 21 may be operated to rotate the gear 15. Since the gear 24 will be driven through idler 23 by the gear 15 through a number of rotations for each rotation of the gear 15, the mandrel 69 will be rotated a number of times proportional to but much greater than the number of rotations imparted to the lead screw 30. The coarseness of the thread of the lead screw is such that the block 35 and the post 65 carried thereby will evenly distribute the coil 110 of wire 68 on the mandrel, as illustrated in Figs. 5 and 6. As the guide member 66 approaches the end of the cylindrical portion 100 of the mandrel, the abutment screw 73 carried by the post 65 35 will engage the pin 75 on the slide rod 76, there-

by to rock the lever 81 clockwise and apply spring pressure to the locking plunger 80, pressing the plunger against the right hand surface (Figs. 1 and 4) of the gear 15. As soon as the gear 15 arrives in the position where the recess 92 is in alignment with the plunger 80, the plunger will snap into the recess 92 and prevent further rotation of the gear 15. The gear ratios and the position of the recess 92 are so arranged that the rotation of the gear 15 will be stopped as soon as the last convolution of the coil 110 has been wound on the body portion 100 of the mandrel and the operator may then release the locking cam 84, which will move the tapered pin 41 out of engagement with the lead screw 30 and simultaneously release the block 35 so that the spring 61 may rock it to the dot and dash position shown in Fig. 2. It should be noted that the spring 71 will maintain tension on the strand of wire 68 and the convolutions forming the coil 110 will be held on the mandrel until the operator manually snubs the wire by bending it over the flat edge of the semi-cylindrical portion 102 of the mandrel around the pin 109 and then through the slot 108. In the operation of the apparatus, a number of mandrels 69 are provided and after the filaments have been wound on the mandrels, they may be treated while still locked in place thereon.

What is claimed is:

1. A coil winding apparatus comprising a main drive shaft, a lead screw on said shaft, a distributor block slidably mounted on said shaft, means carried by said distributor block for guiding material to be wound, means on said distributor block engageable with said lead screw, and a single cam means operable to lock the distributor block in operative position and to engage the means on the distributor block with the lead screw.

2. A coil winding apparatus comprising a mandrel, a mandrel head for receiving said mandrel, a guide member for guiding a strand to said mandrel, a distributor block for supporting said guide member, a main drive shaft for driving the distributor block and the mandrel head, means interconnecting the main drive shaft and the mandrel head, a locking plunger engageable with said last mentioned means to block motion thereof, and means actuated by said distributor block for rendering the locking plunger operable.

3. A coil winding apparatus comprising a main drive shaft, a driving gear mounted on said shaft, a lead screw mounted on said shaft, a mandrel for winding a coil, means interconnecting the driving gear and said mandrel, a distributor actuating pin engageable with said lead screw, a distributor for guiding a strand to the mandrel, said distributor being tiltable to operative asso-

ciation with the mandrel, and means for locking the distributor in operative association with the mandrel and simultaneously engaging the distributor actuating pin with the lead screw.

4. A coil winding apparatus comprising a main drive shaft, a driving gear mounted on said shaft, a lead screw mounted on said shaft, a mandrel for winding a coil, means interconnecting the driving gear and said mandrel, a distributor actuating pin engageable with said lead screw, a distributor for guiding a strand to the mandrel, said distributor being tiltable to operative association with the mandrel, means for locking the distributor in operative association with the mandrel and simultaneously engaging the distributor actuating pin with the lead screw, and means actuated by the distributor in moving to a predetermined point for blocking further rotation of the main drive shaft.

5. A coil winding apparatus comprising a main drive shaft, a driving gear mounted on said shaft, a lead screw mounted on said shaft, a mandrel for winding a coil, means interconnecting the driving gear and said mandrel, a distributor actuating pin engageable with said lead screw, a distributor for guiding a strand to the mandrel, said distributor being tiltable to operative association with the mandrel, means for locking the distributor in operative association with the mandrel and simultaneously engaging the distributor actuating pin with the lead screw, and means actuated by the distributor in moving to a predetermined point for blocking further rotation of the main drive shaft, including a pivoted lever, a slide rod for actuating said lever, an abutment on the distributor for actuating the slide rod, and a spring pressed plunger operable by said pivoted lever.

6. A coil winding apparatus comprising a mandrel, a distributor for directing wire to the mandrel, means interconnecting the mandrel and distributor to drive them at proportional speeds, and a single cam for locking the distributor in position to guide material to the mandrel and to interconnect the distributor with the driving means.

7. In a coil winding apparatus, a mandrel and a distributing mechanism for guiding material to said mandrel including a lead screw for moving the distributor axially of the mandrel, resilient means for urging the distributor away from the mandrel, locking means operable to hold the distributor in operative association with the mandrel, means for interconnecting the distributor and the lead screw, and means operable by said locking cam for disengaging the said last mentioned means from the lead screw.
